UNITED STATES PATENT OFFICE.

LEM ARNOLD, OF SAN ANGELO, TEXAS.

STEAM-EXPANDING DEVICE.

Application filed March 8, 1923. Serial No. 623,782.

To all whom it may concern:

Be it known that I, LEM ARNOLD, a citizen of the United States, residing at San Angelo, in the county of Tom Green and State of 5 Texas, have invented certain new and useful Improvements in Steam-Expanding Devices, of which the following is a specification.

My invention relates to improvements in steam expanders for smoke stacks, such as 10 the smoke stacks of railway locomotives.

The invention has for its object to improve the steam expander disclosed in United States Patent #831,785, granted to C. A. Gilmore, under date of September 25, 1906.

15 The device of this patent embodies an inverted cone arranged in the lower part of the stack, in alinement with the exhaust steam nozzle. This inverted cone expands the steam passing around the same, thus 20 tending to fill the cross sectional area of the stack. It has been found that this device will not operate wholly satisfactorily, as the expanded steam breaks at the upper large end of the inverted cone, moving rapidly inwardly, thus breaking the vacuum or 25 suction in the stack.

I have discovered that this decided disadvantage may be overcome by the improvements which I have made. My improved device embodies an expanding element, which 30 tapers downwardly from its point of maximum diameter, and has a part extending upwardly above the maximum diameter and tapering upwardly. This upwardly tapering part is preferably slightly shorter than the lower tapering part, and also the taper in the upper part is preferably not so pronounced. The lower downwardly tapering part serves to expand the steam, in a proper 35 manner to completely fill the stack at the point of the maximum diameter of the device, while the upwardly tapering part produces a stream-line effect, preventing the breaking of the steam, at the point of maximum diameter of the device, and hence preserves the vacuum or suction in the stack. The upwardly tapering part, prevents violent agitation of the steam, at the said point of maximum diameter, and the reduced end 45 of this part is arranged at a point remote from the point of maximum diameter, and there is no tendency to break the steam or vacuum at the point of maximum diameter.

In the accompanying drawings forming a 50 part of this specification, and in which like

numerals are employed to designate like parts throughout the same,

Figure 1 is a side elevation of a device embodying my invention, showing the same arranged in the stack of a railway locomotive, which is shown in section, and

Figure 2 is a horizontal section taken on line 2—2 of Figure 1.

In the drawings, wherein for the purpose of illustration is shown a preferred embodiment of my invention, the numeral 5 designates the stack of a railway locomotive, carried by the boiler 6, and arranged in concentric relation to a steam exhaust nozzle 7.

My improved expanding device is designated as a whole by the numeral 8, and is shown as arranged concentrically within the stack 5, near its lower end. This expanding device embodies a lower downwardly tapering expanding part 9, and an upper upwardly tapering stream-line part 10, these parts being preferably formed integral. The large ends of these tapering parts unite at a point 11, constituting the maximum diameter of the expanding device. The expanding device is preferably so arranged within the stack 5 that the lower downwardly tapering expanding part 9 projects downwardly below the stack 5 for a slight distance.

Rigidly secured to the upper end of the upper part 8 is a rod 12, rigidly held within a strap 13, carried by a transverse supporting bar 14, which is bolted within the stack 5, as shown at 15. The bar 14 is arranged slightly to one side of the center of the stack so that the rod 12 is arranged concentrically within the stack.

It is obvious that the expanding device may be made in various sizes, depending upon the size or diameter of the particular stack in connection with which it is used. For instance, I have found that advantageous results may be obtained by employing an expanding device having a maximum diameter at the point 11 of $5\frac{1}{2}$ inches, when arranged in a stack having a diameter of 18 inches. The lower expanding part 9 may have a length of 18 inches while the upper expanding part 8 has a length of 10 inches and tapers to a diameter of 2 inches, at the upper end thereof. The lower expanding part 9 tapers to a sharp point. By having the lower expanding part 9 of greater length than the upper stream-line

part 8, a more gradual and complete expansion of the steam is effected, after leaving the exhaust nozzle, while the upper tapered stream-line part prevents the breaking 5 of the expanded steam, due to violent agitation.

It is obvious that the device may be made of cast iron, sheet metal, or any other suitable material.

10 When the device is installed in the stack of a railway locomotive, as indicated in Figure 1, the exhaust steam passes from the upper end of the nozzle 7 around the downwardly tapering expanding part 9, and the 15 steam is expanded thereby, the maximum expansion occurring at the point 11, which is the maximum diameter of the expanding device. The cross sectional area of the stack therefore becomes filled with the expanded 20 steam, which is essential to a proper suction or vacuum within the stack. As the steam proceeds upwardly through the stack, beyond the point 11, the upwardly tapering stream-line part 10 will prevent the breaking 25 of the expanded steam, due to violent agitation of the same. The upper end of the part 10 being remote from the point 11, any agitation occurring at this point, will not materially effect the vacuum at the point 11. 30 It has been found that there is very little, if any, undue agitation of the steam at the upper end of the stream-line part 10.

It is to be understood that the form of my invention herewith shown and described is 35 to be taken as a preferred example of the same, and that various changes in the shape, size, and arrangement of parts may be resorted to, without departing from the spirit of my invention or the scope of the sub- 40 joined claims.

Having thus described my invention, I claim:

1. The combination with the smoke stack 45 of a railway locomotive, of a steam nozzle arranged beneath the same, and a steam expanding device concentrically arranged within the smoke stack, said device embody-

ing a lower downwardly tapering steam expanding conical part and an upwardly tapering stream-line frustro-conical part, said 50 parts having their large ends arranged at a point constituting the maximum diameter of the device, the upper end of the stream-line part terminating at a point remote from said maximum diameter.

2. The combination with the smoke stack of a railway locomotive and a steam nozzle discharging into the same, of a steam expanding device concentrically arranged within the lower portion of the smoke stack, 60 said device embodying a lower downwardly tapering steam expanding conical part and an upper upwardly tapering stream-line part which is circular in horizontal section, 65 said parts being arranged in end to end relation, the expanding part having a greater length than the stream-line part.

3. The combination with the smoke stack of a railway locomotive and a steam nozzle discharging into the lower end of the same, 70 of a steam expanding device arranged in concentric spaced relation within the lower portion of the stack and being circular in horizontal cross section, said device having a point of maximum diameter and tapering 75 downwardly from said point in the form of a steam expanding part and tapering upwardly from said point in the form of a stream-line part.

4. The combination with the smoke stack 80 of a railway locomotive and a steam nozzle discharging into the lower end of the same, 85 of a steam expanding device arranged concentrically within the lower portion of the stack, said device having a point of maximum diameter and tapering downwardly 90 from said point in the form of a steam expanding part and tapering upwardly from said point in the form of a stream-line part, said expanding part having a greater length and a higher pitch of taper than the stream-line part.

In testimony whereof I affix my signature.
LEM ARNOLD.
